MOTHER SHIP FOR WATERCRAFTS

Walter W. Reedy, Sr., Lebanon, Pa.

Application March 17, 1942, Serial No. 435,091

1 Claim. (Cl. 104—135)

This invention relates to mother ships for water crafts employed for war purposes, and has for the primary object the provision of a ship of the above stated character which may be provided with the usual fighting equipment of a battleship or similar vessel for attacking and defensive purposes and in addition thereto will have berth facilities for a large number of speedy small water crafts and means for quickly and safely launching said small crafts at will so that they may be employed in attacking the enemy in large numbers, each offering an extremely small target for the enemy and possessing tremendous destructive power and speed.

Another object of this invention is the provision of facilities on the mother ship for the repair, fueling and the resupplying of the small fighting crafts with ammunition of the desired kind, also for reequipping said crafts with guns and other firing devices as need therefor occurs.

A further object of this invention is the provision of a launching device which besides assuring quick and safe launching of the small water crafts, also includes means for the reberthing of said crafts after the return thereof to the mother ship from an attack on the enemy or from other war maneuvers.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is a side elevation, partly in section, illustrating a mother ship constructed in accordance with my invention and showing a plurality of small speedy fighting water crafts berthed therein ready for launching.

Figure 2 is a top plan view partly broken away showing the mother ship and the accommodation of the small water crafts therein.

Figure 3 is a fragmentary longitudinal sectional view showing the means of releasably securing the small crafts in berthed position and also showing the means of reberthing the small crafts.

Figure 4 is a fragmentary transverse sectional view taken through the line 4—4 on Figure 5, looking in the direction of the arrows.

Figure 5 is a fragmentary vertical sectional view showing one of the small fighting crafts berthed and the means of releasing the same for launching.

Figure 6 is a rear elevation showing the doors for opening and closing the runways of the mother ship at the stern of said ship.

Figure 7 is a fragmentary perspective view illustrating a bar and one of its clamps for the quick attachment thereof to one of the endless cables employed in the reberthing of the small water crafts.

Referring in detail to the drawings, the numeral 5 indicates a mother ship or carrier for small speedy fighting water crafts designated generally by the character 6. Crafts of this character are now in use for fighting purposes, possessing a maximum amount of destructive power for the size thereof, high rates of speed and owing to the smallness thereof, offer extremely small targets for the enemy. Of course, a craft of this kind has a limited cruising radius and now are only used within a limited distance from a shore base. However, through the use of the proposed invention such small speedy fighting crafts may be employed on water wherever the enemy may be located. The invention permits the foregoing to be successfully carried out.

The mother ship 5, as before stated, may be provided with the usual fighting equipment of a battleship or similar vessel so that it may be employed for attacking and defensive purposes. Constructed in the hull of the ship 5 are parallel inclined runways 7 opening outwardly of the hull at the stern of the ship 5 and normally closed by doors 8 hingedly mounted, as shown at 9, so that said doors may open by gravitation. Suitable hoisting means 10 is provided for closing the doors and also may be employed for limiting the downward movement of the doors below the surface of the water.

The runways 7 extend from the stern of the ship 5 to a point within the bow construction of said ship to give a maximum berthing facility for the crafts 6. The bow construction of the ship 5 at the upper or head ends of the runways is preferably constructed to provide a workshop 11 wherein various equipment may be arranged, for the repair, fueling and resupplying of the small water crafts berthed in the runways. It is to be understood that conventional traveling cranes may be provided in the hull of the ship 5 to facilitate the handling and loading of supplies for the small crafts 6.

Each runway 7 includes an inclined track construction 12, consisting of a bottom wall 13, diverging side walls 14 and substantially horizontal portions 15 providing walkways and supports for

a part of the reberthing mechanism. Suitable braces 16 support the portions 15 and the bottom wall 13 at spaced intervals is equipped with rollers 18 each including substantially conical shaped portions so that said rollers will more or less take on the general contour of the bottoms of the crafts 6, permitting said crafts to move over the track construction with a minimum amount of friction. The lower end of the track construction terminates at the stern of the ship 5 below the surface of the water, so that when the doors are open the crafts 6 may float off of or onto the track construction.

A plurality of chocks 17 are arranged on the track construction to swing upwardly and downwardly relative thereto, and when swung upwardly are adapted to be abutted by the bows of the crafts 6 for sustaining them on the inclined track construction preferably spaced from each other in order that said crafts may be conveniently cared for still supporting said crafts as closely as possible to each other for the purpose of conserving space and permitting the greatest possible number of crafts to be accommodated on the track within the hull of the vessel or ship 5.

It is preferable that the chocks be shaped to conform to the contour of the bows of the crafts 6 when in engagement therewith and are secured to shafts 19 journaled transversely of the track below the bottom wall 13 thereof.

Handles 20 are provided for the shafts 19 for swinging the chocks upwardly and downwardly and are provided with pins 21 to be engaged by treadle type latches 22 for releasably sustaining the chocks in upright or holding position the levers 20, together with the treadle latches 22, being mounted in juxtaposition to the outer side of each of the horizontal portions or walkways 15 (catwalks), at the outer sides only of the runways 7, the lower ends of the levers extending downwardly through the deck 5 for connection with the shafts 19, substantially as shown in figures. The bottom wall 13 of the track construction may be provided with slots in which the chocks 17 may be positioned when lowered so as not to interfere with the movement of the crafts 6 over the track construction.

Power driven drums 24 are arranged adjacent the head ends of the track construction and have endless cables 25 passed several times thereabout. The endless cables are trained over a series of pulleys 26 on the track construction so that said endless cables extend the full length of the track construction and with upper and lower runs, the upper runs being disposed over the portions 15 of the track construction.

Loading bars operate in conjunction with the upper runs of the endless cables in reberthing the crafts within the hull of the ship 5, a fragmentary portion of one of said bars being shown in Figure 7 and indicated by the character 23'. Suitable quick detachable clamps 26' are connected with the ends of the bar 25' to permit the application and removal of the bar to the upper runs of the endless cables. It is to be understood that in the reberthing of the crafts 6 in the ship 5 the bars 25' are employed to engage with the end of the craft to be loaded so that on the rotation of the drums 24, the craft will be moved along the inclined track construction of the runway to a point where it is to be berthed and a chock is moved into an upright position sustaining the craft in its berthed position ready

for immediate launching or to have other operations carried out thereon as explained in the foregoing.

It is to be understood that the clamps 26' may be of any well known quick detachable type so that the application and removal of the bars to the endless cables can be quickly and successfully carried out. The bars are removed from the endless cables when they reach the head ends 10 of the runways or when a particular craft has reached its berthing position.

From the foregoing description taken in connection with the accompanying drawings, it will be seen that a very efficient and practical carrier 15 for small speedy fighting water crafts has been provided capable of travel along with other war vessels and will at the time of engaging an enemy be capable of attacking as well as defensive purposes and that at the time of engagement a large number of speedy small fighting crafts can be successfully and safely launched therefrom in order that the small crafts can be utilized in attacking the enemy with tremendous destructive power and still offer comparatively small targets 20 for the enemy. Also a ship of the kind described 25 may be successfully employed for convoy duty and against attacking submarines.

Further, it will be seen that the small crafts 30 can be easily and quickly reberthed within the ship and serviced and relaunched if further attacks are to be made immediately or may be reberthed for transportation by the ship until again needed for attacking the enemy.

While I have shown and described the preferred embodiment of my invention, it will be understood that minor changes in construction, combination and arrangement of parts may be made without departing from the spirit and scope of the invention as claimed.

Having thus described my invention, what I claim is:

In a berthing and launching device for small water craft on ships, an inclined track construction mounted in a ship and extending forwardly 45 from an entrance in the stern of the ship, said track construction including a bottom wall with side diverging walls and horizontal portions providing catwalks at each side of the track construction, anti friction rollers rotatably supported by the bottom wall for the support of small craft movable over the track construction, shafts journaled on the track construction and extending under the bottom wall, said bottom wall having slots above said shafts, elongated channeled 50 chocks normally closing said slots and secured to the shafts and movable thereby, hand levers secured to the shafts and extending through said deck alongside certain of the horizontal portions for operation by a person standing on the latter 55 to move the chocks to positions at substantially right angles to the bottom wall to engage the bows of the small craft, treadle type latches mounted adjacent said levers to engage the levers to releasably sustain the chocks in the stated positions and to permit freeing of the levers for the movement of the chocks to normal positions and thereby permit the small craft to gravitate downwardly of the track construction, and a power operated means for moving the small craft to berthed positions upwardly along the track construction and supported by the horizontal portions of the track construction.
